[57] **CLAIM**

The ornamental design for a set of food-forming molds, as shown and described.

DESCRIPTION

FIG. 1 is a top plan view of a first mold from the set of food-forming molds showing my new design;

FIG. 2 is a top plan view of a second mold thereof;

FIG. 3 is a top plan view of a third mold thereof;

FIG. 4 is a top plan view of a fourth mold thereof;

FIG. 5 is a top plan view of a fifth mold thereof; and,

FIG. 6 is a top perspective view of FIG. 4, it being understood that FIGS. 1, 2, 3, and 5 are the basically the same.

It is understood that the undisclosed bottom surfaces of all views are flat and unornmented.

It is understood that FIGS. 1–6 constitutes a set and brackets used to show the association of articles within a set have been omitted for convenience of illustration.
